STEAM DELIVERY AND SUPERHEATER
HEADER UNIT

Adolph J. Wegmann, Flushing, N. Y., assignor to
Dri-Steam Products, Inc., a corporation of
Delaware

Application July 23, 1941, Serial No. 403,692

10 Claims. (Cl. 122—459)

This invention relates to locomotive boilers and more particularly to a steam delivery and superheater header unit of novel construction and including a steam drying element in a new and improved relationship therein.

One of the objects and features of the present invention is to provide a steam delivery and header unit for a superheater through which steam is adapted to be fed to the superheater tubes in substantially dry condition and through which the flow of steam is controlled.

Another feature of the invention is to provide a superheater header construction having a drier embodied in the inlet chamber thereof to substantially dry the steam prior to its passage through the superheater.

The above and additional objects and features of the invention will become more apparent when the following detailed description and the appended claims are read in connection with the accompanying drawing, in which:

Fig. 1 is a plan view with parts broken away of one form of steam delivery and superheater header unit of the present invention;

Figure 2 is a vertical sectional view taken substantially along lines 2—2 of Figure 1 and showing in vertical elevation an intake steam and water separator for the dry pipe connection; and

Fig. 2a is a fragmentary view in vertical section of a modified form of superheater header unit.

Referring to Figs. 1 and 2 of the drawing, a domeless type of locomotive boiler 10 is shown fragmentarily to illustrate the location and use of my steam delivery and superheater header units and the intake steam and water separator. The steam and water space 12 of the boiler 10 is divided from the smokebox 14 by a fire tube plate 16. The dry pipe 18 which is provided with an intake steam and water separator 20, the details of which will be described hereinafter, is shown mounted on the fire tube plate 16 by a suitable collar 22 and bolts 24. One form of superheater header unit 25 is shown provided with an inlet connection 26 having a flange 28 through which the bolts 24 pass to mount the unit on the plate 16 in communication with the dry pipe 18.

The steam delivery and superheater header unit 25 of my invention comprises a unitary housing having an inlet chamber 32 and an outlet chamber 34. The two chambers are separated by a partition 36 which zig-zags back and forth as shown in Fig. 1 to provide passages establishing communication with the alternately arranged

openings 38 and 39 which, in turn, establish communication with suitable superheater tubes 37.

The inlet connection 26 extends into the chamber 32 of the unit 25 and is provided with an elbow 40 which opens upwardly in communication with the upper part of the chamber. An upwardly extending annular flange 41 is provided in the chamber 32 and spaced between the upwardly extending portion of the elbow 40 and the side wall 42 of the chamber. The space 43 between the flange 41 and the wall 42 is provided with a drain connection 44. The space between the elbow 40 and the flange 41 provides a passageway for the downward flow of steam to the superheater connections 39.

Supported on the upper end 46 of the elbow 40 is an annular disc-like member 48. The member 48 is provided with an upwardly extending peripheral flange 50 within which an annular steam baffle 52 is adapted to be held. The member 48 and the baffle 52 are adapted to be positioned within the chamber 32 through a top opening in the chamber which is provided with a cover 54. When the baffle is in position on the member 48 the cover 54 is adapted to engage and hold the baffle and the member 48 in position.

The baffle 52 is provided with two series of inclined blades 56 which are formed between slots cut into the baffle. Steam entering through the connection 26 is deflected by the blades 56 outwardly into the chamber 32 obliquely against the side wall 42. The inclination of the blades 56 directs the steam and particles of water entrained by the steam in a swirl outwardly and downwardly along the wall 42 and in the direction of the space 43. In order for the steam to pass inwardly of the flange 41 the steam must first undergo a reversal in the direction of flow 45 and pass over the flange 41. The brushing engagement of the steam along the surface of the side wall 42 and the reversal in direction throws into the space 43 substantially all of the particles of water entrained in the steam. The steam thus reaching the lower part of the chamber 32 for passage through the superheater connections 39 is substantially dry, thereby insuring a superheated steam of higher temperature.

The outlet chamber 34 is provided with a throttle valve 60, the lower portion of the chamber being formed with a partition 62 having an aperture 64 about which a valve seat 66 is provided. The throttle valve 60 is provided with the usual control connections 68 mounted in a cover 70 on the upper part of the chamber 34.

The lower portion of the chamber 34 is provided with a steam delivery outlet 72 to which a pipe 74 may be connected.

Referring to Fig. 2a of the drawing, I show another embodiment of the steam delivery and superheater header unit of my invention wherein a compact and different drier construction is used. The header unit comprises a unitary housing 125 similar to the housing of the embodiment shown in Figs. 1 and 2. The housing 125 encloses an inlet chamber 132 and an outlet chamber 134 divided by a partition 136. The housing is provided on opposite sides of the partition with groups of openings to which superheater tubes 137 are adapted to be connected.

The inlet connection 126 to the housing 125 opens directly into the chamber 132. Disposed in the lower portion of the chamber 132 is an annular flange 140 which extends upwardly in spaced relation to the side wall 142 of the chamber so as to provide an annular trough 143 to which a drain outlet 144 communicates. The upper portion of the annular flange is provided with a shoulder 146 upon which is mounted an annular baffle 148. The baffle 148 has numerous small protruding nozzles 149 on the outer surface thereof, similarly as disclosed in the United States Patent No. 2,149,626, through which the steam is adapted to be combed in its passage through the chamber 132. A second annular baffle 152 is adapted to be disposed concentrically about and in spaced relation to the baffle 148. The lower portion of the baffle 152 is supported by an annular element 153 shaped to rest on and along the bottom of the trough 143, except for a portion 154 adjacent the drain 144 whereby the spaces on both sides of the baffle 152 are maintained in communication with the drain. The housing 125 is provided with an opening having a cover 155 through which the baffles 148 and 152 and the element 153 are installed. The cover 155 when in covering position bears against the upper edges of the baffles 148 and 152.

The baffle 152 is provided with a plurality of slots shaped to form blades 156 therebetween slightly inclined to direct steam obliquely downwardly and circumferentially across and against the protruding nozzles of the baffle 148. This oblique flow of steam across the protruding nozzles 149 subjects the steam to a severe brushing and combing action which effectively removes substantially all of the particles of water entrained by the steam. The water thus removed drains into the trough 143 and is removed through the drain 144. The steam passing through the baffle 148 enters the superheater connections on the inlet side of the partition 136. After the steam has been subjected to superheating temperatures in the superheater coils it is returned to the outlet chamber 134 and thence to the usual throttle valve, such as shown in Fig. 2.

From the foregoing it will be recognized that the superheater header units of my invention are compact, sturdy, economical to build and easy to assemble and install. The units can be used with any suitable superheater and with their drier construction insure a delivery to the superheater of substantially dry steam, the flow of which can be controlled by the associated throttle valve.

While I have shown two embodiments of the steam delivery and superheater header unit I recognize that many variations and different embodiments of the invention are possible. It is to be understood, therefore, that the forms shown

in the figures of the drawing are to be regarded as illustrative only and not in restriction thereof.

I claim:

1. A steam delivery and header unit for a superheater comprising a unitary housing having inlet and outlet chambers, a steam drier in the inlet chamber to remove particles of moisture from the steam prior to the passage of the steam through the superheater, a throttle valve in the outlet chamber to control the flow of steam, a partition between said chambers, connections on opposite sides of said partition for connection thereto of the tubes of the superheater, and a wall disposed in said inlet chamber in association with said drier to provide a passageway for steam on one side thereof and another passageway for particles of water on the other side thereof.

2. A steam delivery and header unit for a superheater comprising a unitary housing having inlet and outlet chambers, a steam drier in the inlet chamber to remove particles of moisture from the steam prior to the passage of the steam through the superheater, a throttle valve in the outlet chamber to control the flow of steam, a partition between said chambers, tube connections along said partition with alternate connections disposed on opposite sides of the partition, a wall disposed in said inlet chamber in association with said drier to provide a passageway for steam on one side thereof and another passageway for particles of water on the other side thereof, and said drier including an apertured member disposed above said wall to impart a whirling motion to the steam adjacent said wall.

3. A steam delivery and header unit for a superheater comprising an integral housing having inlet and outlet chambers with a partition therebetween, superheater connections on opposite sides of said partition, an annular flange disposed in said chamber to provide an annular trough adjacent the side walls of said chamber, an annular baffle disposed within said chamber and having a plurality of parallelly aligned inclined slots, means to support the baffle to cause steam to pass through said slots and means to support a throttle valve in the outlet chamber to control the flow of steam.

4. A steam delivery and header unit for a superheater comprising a housing having inlet and outlet chambers having superheater connections in communication therewith, an inlet connection extending into said inlet chamber, a flange disposed between said connection and a wall of said inlet chamber to provide a passageway for steam on one side of the flange and a passageway for particles of water on the other side of the flange, and a baffle adjacent said connection to direct the steam for brushing engagement against said wall to separate particles of water from the steam.

5. A steam delivery and header unit for a superheater comprising a housing having inlet and outlet chambers with superheater connections in communication therewith, an inlet connection extending into and communicating with the inlet chamber, an annular flange disposed in spaced relation between said inlet connection and the side wall of said inlet chamber, a liquid drain communicating with the space between said flange and said side wall, and an annular baffle having parallelly aligned inclined slots disposed adjacent said inlet connection to direct the steam obliquely against said side wall.

6. A steam delivery and header unit for a superheater comprising a housing having inlet and outlet chambers with superheater connections in communication therewith, an inlet connection extending into and communicating with the inlet chamber, an annular flange disposed in spaced relation between said inlet connection and the side wall of said inlet chamber, a liquid drain communicating with the space between said flange and said side wall, an annular disc-like element supported on the inlet connection and an annular member supported on said element having a portion slotted and shaped to form blades inclined to direct the steam obliquely against the side wall for swirling movement therealong.

7. A steam delivery and header unit for a superheater comprising a housing having inlet and outlet chambers with superheater connections in communication therewith, means including an annular flange disposed within the inlet chamber and in spaced relation to the side walls thereof, a liquid drain communicating with the space between said flange and said side wall, an annular member having numerous small protruding nozzles, said member being disposed in said chamber above said flange, and an annular baffle disposed between the said member and the side wall of said chamber, said baffle having a portion thereof slotted and shaped to form blades inclined to direct steam obliquely against the nozzles contained in the first mentioned baffle.

8. A steam delivery and header unit for a superheater comprising a housing having inlet and outlet chambers with a partition therebetween, superheater connections on opposite sides of said partition, an annular flange disposed in said chamber with passages on opposite sides thereof, one passage for the flow of steam and the other

passage to remove particles of moisture separated from the steam, an annular baffle disposed within said chamber and having a plurality of parallelly aligned inclined slots, and means to support the baffle to cause steam to pass through said slots and undergo a whirling movement to effect separation of moisture therefrom.

9. A steam delivery and header unit for a superheater comprising a housing having inlet and outlet chambers with superheater connections in communication therewith, an inlet connection extending into said inlet chamber, a flange disposed between said connection and a wall of said inlet chamber to provide a passageway for steam on one side of the flange and a passageway for particles of water on the other side of the flange, and an annular baffle associated with said connection and disposed above said flange to subject the flowing steam to a whirling movement to separate therefrom any particles of moisture contained therein.

10. A steam delivery and header unit for a superheater comprising a housing having inlet and outlet chambers with superheater connections in communication therewith, means including an annular flange disposed within the inlet chamber and in spaced relation to the side walls thereof to provide a passageway for steam on one side of the flange and a passageway for particles of water on the other side of the flange, an annular member having numerous small protruding nozzles disposed in said chamber above said flange, and an annular baffle disposed adjacent the said member and having a portion thereof slotted and shaped to form blades inclined to direct steam obliquely against the nozzles contained in the first mentioned baffle.

ADOLPH J. WEGMANN.
